UNITED STATES PATENT OFFICE.

EZEKIEL VAN NOORDEN, OF BOSTON, MASSACHUSETTS.

SWINGING WINDOW.

SPECIFICATION forming part of Letters Patent No. 740,954, dated October 6, 1903.

Application filed April 3, 1903. Serial No. 150,968. (No model.)

To all whom it may concern:

Be it known that I, EZEKIEL VAN NOORDEN, a citizen of the United States, residing at Boston, in the county of Suffolk and State of Massachusetts, have invented a new and useful Improvement in Swinging Windows, of which the following is a full, clear, and exact description, reference being had to the accompanying drawings, forming a part of this specification, in explaining its nature.

My invention relates to an improvement in swinging windows, and especially to that class of window where the sash is pivoted at its center to swing vertically in the frame.

My invention consists in providing the sash in a window of this kind with a set of movable weather-strips to make it tight and secure along its top and bottom edges, where they unite, respectively, with the head and sill of the frame. The weather-strips are in the nature of movable plates or guards that are made to be extended from the top and bottom rails of the sash when closed to unite with the head and sill of the frame, as before referred to, so closing the intermediate space otherwise left between them, but which plates or guards can be withdrawn or made to disappear when the sash is to be swung open.

My invention further relates not only to the means by which this movement of the weather-strips can be obtained, but also to the means by which they may be simultaneously withdrawn and from a common source of power.

The combination of the various parts, together with their mode of operation and various capabilities, can best be seen and understood by reference to the drawings, wherein—

Figure 1 shows a window containing my invention in vertical cross-section. Fig. 2 shows the same in longitudinal vertical section on the line 2 2 of Fig. 1. Fig. 3 shows the same in horizontal cross-section on the line 3 3 of Fig. 1.

Referring to the drawings, A represents the window-frame, and B the window-sash. The sash is pivoted between the head and sill of the frame at the points a a', respectively, to swing in an upright vertical position. Both

the frame and sash may be of any suitable construction or design. They preferably are made, however, as represented, of sheet or rolled metal plate. Concealed in a housing in the grooves or recesses b b', formed, respectively, in the top and bottom rails of the sash, are the plates b² b³. These plates extend in their respective grooves the full width of the sash and are adapted to be partially moved or extended therefrom to make weatherproof jointure with the head and sill of the frame, respectively, thus protecting the top and bottom edges of the sash, which extend contiguously therewith when the sash is closed, the plate b² being extended from the recess b, in which it is contained, into a complementary recess a², formed in the head of the frame, while the plate b³, contained in the recess b', is extended therefrom to lap over the edge a³, formed in the sill thereof.

The plates b² b³ are connected to be simultaneously moved or extended from the recess in which they are contained to make their separate jointures with the frame by means comprising the bars b⁴ b⁵, fixed to said respective plates; the links b⁶ b⁷, pivoted, respectively, to the ends of the bars b⁴ b⁵ at the points b⁸ b⁹, and the rotary disk b¹⁰, to the opposite edges of which the said links are respectively pivoted at the points b¹¹ b¹². These connecting members, comprising the bars, links, and disks, are preferably concealed, it is to be noted, in the hollow vertical extending sash-bar B'. They are hung supported, together with the plates or guards b² b³, which they serve to connect, upon a member taking the form of a key, the shank b¹³ of which extends at one end through the stud b¹⁴, fastened within the sash and in which the shank has bearing and is extended to connect at its other end with the rotary disk b¹⁰ by fastening into a square slot b¹⁵, cut therein. The end of the key passing through the sash-bar has a head b¹⁶, by which the key is turned, and it is to be noted that on the outside of the sash-bar the shank of the key has bearing in a cap b¹⁷, secured thereto and against which the flange b¹⁸, formed on the shank of the key, rests, thus preventing its withdrawal.

The turning of the key has the effect of turning the rotary disk b^{10} , and thereby of simultaneously controlling the movement of the plates $b^2 b^3$ in their relation to the frame.

5 This effect is obtained by reason of the fact that the links $b^6 b^7$ being pivoted to the opposite edges of the disk b^{10} are alternately projected or retracted as the disk is turned, and this motion is utilized for the purpose of 10 projecting or retracting the plates $b^2 b^3$, projecting them so that they make their weatherproof jointure with the head or sill of the frame, as before referred to, when the sash is closed or drawing them back into their 15 recesses in the sash when it is desired to swing the sash open, the size of the disk, the length of the links and connecting bars, and the width of the weatherproof forming plates or guards being so coöordinated that this effect 20 will be obtained when the disk is turned from a vertical to a horizontal position, or vice versa, and this by turning the key on the inside of the sash. And it is to be especially noted that this adjustment of the weather- 25 proof forming plates or guards is obtained with perfect harmony, the plates and their connecting members being so related that they practically balance one another upon the shaft or barrel of the key as a center as 30 the rotary disk is turned, excepting when the links are in line and the plates are extended to make their jointure with the frame, (see Fig. 2,) when a perfectly straight draft is maintained. Besides this capability of the 35 plates for reinforcing the sash by providing it with a weatherproof jointure with the head and sill of the frame, they act also as a means for locking the sash when closed, and such means as can only be unlocked from inside 40 the sash, for, as before said, the key by which these plates are primarily controlled is accessible only from the inside of the sash.

The practical utility of a means like as I have described needs no special mention. It 45 is simple, economical, and effective. It constitutes an independent means which does not in any way interfere with the pivotal or swinging adjustment of the sash. It can be applied for securing the weatherproof jointure and for locking a single sash, or it may be applied to sashes arranged in series, the means being especially capable of simultaneous actuation when applied to a series of windows. Moreover, the means although 50 best applied to the kind of window and in the manner like as I have shown may well be applied to other kinds of window and still be within the essence of my invention. Its application to a horizontally instead of the 55 vertically swinging sash would of course be an obvious expedient.

Having thus fully described my invention, I claim and desire to secure by Letters Patent of the United States—

65 1. A window having a sash pivoted or hung

to swing within the frame, movable plates or guards carried by said sash and which are adapted either to be moved outward from the edges thereof to make jointure with the frame when the sash is closed in order to afford a weatherproof protection therefor, or be retracted into the sash to permit of its being turned open, and means for simultaneously actuating said plates or guards to assume their relative changes in position.

2. A window having a sash pivoted or hung to swing within the frame, movable plates or guards concealed within the sash-bars to the sash which are adapted either to be moved outwardly therefrom to unite with the frame 80 so as to afford a weatherproof protection for the edges of the sash that conjoin therewith when the sash is closed, or be retracted into the sash so as to permit of its turning upon means adapted to be accessibly influenced 85 from within the sash for simultaneously actuating said plates or guards to assume their relative changes in position.

3. A window having a sash pivoted or hung to swing within the frame, grooves or recesses 90 formed in the top and bottom rails of said sash plates or guards contained within the said recesses and which are adapted either to be moved out therefrom to unite with the head and the sill of the frame respectively 95 so as to afford a weatherproof protection for the top and bottom edges of the sash that conjoin therewith when the sash is closed, or be moved to be entirely contained within the said recesses to permit of the sash turning 100 open, and means adapted to simultaneously move said plates or guards whereby they may unite with the frame as aforesaid or be retracted into the recesses or grooves formed in the sash.

4. A window having a pivoted sash, grooves or recesses formed in said sash along alternate edges thereof, plates or guards contained within said grooves or recesses, and which are adapted to be partially moved out therefrom to conjoin with the corresponding edges of the frame, and means for simultaneously controlling said plates or guards to be extended partially from or retracted into the said grooves or recesses in which they are 115 contained comprising links and a rotary disk to the opposite edges of which the said links are pivoted, and means for controlling said rotary disk, substantially as and for the purposes set forth.

5. A window having a sash pivoted to turn upright within the frame, grooves or recesses formed in the top and bottom rails of said sash, plates or guards contained within said grooves or recesses, and which are adapted 125 to be moved out partially therefrom, the upper of said plates to enter a groove or recess formed along the head of the frame, the lower plates or guards to lap contiguously with an edge formed in the sill thereof, and concealed 130

means for simultaneously controlling said plates or guards to be partially extended from or retracted into the grooves or recesses in which they are contained comprising links, 5 a rotary disk to the opposite edges of which said links are pivoted, and a shaft or key engaging in the said disk and accessibly to be

turned from inside the sash, substantially as described.
